UNITED STATES PATENT OFFICE.

CHARLES N. TYLER, OF BUFFALO, NEW YORK.

SIPHON.

SPECIFICATION forming part of Letters Patent No. 357,645, dated February 15, 1887.

Application filed December 18, 1885. Serial No. 186,025. (No model.)

To all whom it may concern:

Be it known that I, CHARLES N. TYLER, a citizen of the United States, and residing at Buffalo, in the county of Erie and State of New York, have invented a certain new and useful Improvement in Siphons, of which the following is a specification.

My invention is a siphon constructed as fully set forth hereinafter, whereby the efficiency of the apparatus is greatly increased and the withdrawal of a fluid from a vessel or tank may be easily regulated.

In the drawings, Figure 1 is a sectional elevation of a tank, showing my improved siphon applied thereto. Fig. 2 is a front elevation. Fig. 3 is a plan. Fig. 4 is a detached enlarged view of the nozzle portion of the siphon. Fig. 5 is a detached section illustrating the junction of the flexible and rigid portions of the siphon. Fig. 6 is a perspective view of the guide-block. Fig. 7 is a perspective view of the clamp.

The siphon consists of a rigid tube, A, preferably of metal, a flexible tube, B, connected to the upper end of the tube A, a nozzle, C, and a transparent tube, a, arranged in the line of the flexible tube B, preferably adjacent to the nozzle C; and to the tube B, adjacent to the nozzle, is also secured a hook, b, or other suitable retaining device, whereby the end of the tube B may be readily secured to and detached from any suitable support—as, for instance, the edge of a tank or vessel, D, containing the fluid which is to be drawn off into any other suitable receptacle.

In connection with the siphon constructed as above described, I use certain attachments—as, for instance, a clamp, E, consisting of a yoke of spring metal, e, secured to a ring, c, encircling the tube B, the said clamp being constructed, as shown, so that its fingers will grasp between them a cross-bar, d, laid upon the edge of the tank D, thereby supporting the ring c in such position that the tube A may be passed through the same into the tank, the ring supporting the parts in the position shown in Fig. 1. Another attachment is a guide-block, F, having a groove, x, adapted to receive the edge of the tank, and a curved edge 50 with a peripheral groove, i, therein, and pins m,

projecting from opposite sides of the groove, so that the tube B may be laid in the groove and will be retained by the pins, thereby preventing it from being flattened by its own weight, and from being bent at such an abrupt angle as would restrict the opening and prevent the passage of fluid. Another attachment is a ring, G, preferably consisting of a coil of wire, which encircles the tube B, to which ring the hook b is attached, as shown.

I prefer to make the nozzle C in the form of a bent tube provided with a cock, f; but it is not necessary to use this cock in all cases, as the nozzle may consist of a prolongation of the flexible tube, which may be closed by flattening it by pressure between the finger and thumb. The tube B is expanded to fit over the upper end of the rigid tube A, and is generally extended so as to cover a small recess, y, in the end of the tube A, which recess may 70 be uncovered by drawing the tube B slightly upward whenever it is desired to admit air to the siphon to arrest the siphoning of the fluid.

When the parts are arranged as shown in Figs. 1, 2, and 3, the siphon may be started by 75 inserting the nozzle C in a small vessel of water a number of times and manipulating the tube B, so as to collect the water therein and impart a motion thereto from the bent portion over the guide F toward the nozzle, when this 80 traveling body of water will operate as a piston to pump an additional quantity from the tube A into the tube B and start the flow of the water, after which it will continue to flow so long as the nozzle C is below the level of 85 the surface of the water in the tank. The flow of the water is arrested either by turning the cock f or by carrying the nozzle to a point above the surface of the water in the tank, and the height of the water in the tank may at any 90 time be readily ascertained by carrying the tube upward or downward until the surface of the water can be seen in the transparent section a, which will of course correspond to the level of that in the tank.

The nozzle may be supported in position above the surface of the water by suspending it by means of the hook b to the edge of the tank D, and the flow of water can at once be started at any time by disengaging the hook b 100

from its support and carrying the nozzle to a position below the water-level. The nozzle, therefore, may be manipulated so as to serve as a faucet to regulate the flow of the water.

5 It will be evident that the block F may be constructed of different forms to serve as a guide, and it may be provided with a clamp to secure it fixedly upon the edge or any other part of the tank D.

10 In order to prevent the end of the tube A from being closed when the tube is in contact with the bottom of the tank, it is provided with a side notch or opening, s, as shown in Fig. 1.

15 In some instances the other features described may be used without the rigid tube A, the flexible tube extending to the bottom of the tank. Without limiting myself to the precise con-

struction and arrangement of parts shown and described, I claim—

1. A siphon consisting of a rigid tube, A, 20 a flexible tube, B, a nozzle, and a transparent section, a, in the line of the flexible tube B, substantially as set forth.

2. The combination, i. a siphon, of a flexible tube, B, and rigid tube A, having a recess, 25 y, substantially as and for the purpose described.

In testimony whereof I have signed my name to this specification in the presence of two subscribing witnesses.

C. N. TYLER.
